CLAIM

We claim the ornamental design for a lint roller, as shown and described.

DESCRIPTION

FIG. 1 is a top plan view of one embodiment of a lint roller comprising a new, original and ornamental design;

FIG. 2 is a left side elevational view of the lint roller shown in FIG. 1;

FIG. 3 is a right side elevational view of the lint roller shown in FIG. 1;

FIG. 4 is a left side perspective view of the lint roller shown in FIG. 1;

FIG. 5 is a right side perspective view of the lint roller shown in FIG. 1;

FIG. 6 is a cross-sectional view taken along line 6-6 of FIGS. 2-3, of the lint roller shown in FIG. 1;

FIG. 7 is a cross-sectional detail view of the area marked "see FIG. 7" in FIG. 6, of the lint roller shown in FIG. 1;

FIG. 8 is a cross-sectional detail view of the area marked "see FIG. 8" in FIG. 6, of the lint roller shown in FIG. 1;

FIG. 9 is a cross-sectional view taken along line 9-9 of FIGS. 2-3, of the lint roller shown in FIG. 1; and,

FIG. 10 is a cross-sectional view taken along line 10-10 of FIG. 2, of the lint roller shown in FIG. 1.
